SECTIONAL TOOL CABINET

Ray Clink, Sedro Wooley, Wash.

Application September 27, 1946, Serial No. 699,932

1 Claim. (Cl. 312—107)

1

This invention relates to a tool cabinet which is particularly adapted for use in garages and other places where work is done upon automobiles and the like. It is one object of the invention to provide a tool cabinet of such construction that it may be easily moved from one place to another and thus allow the cabinet to be moved to a position close to the automobile to be repaired and tools placed within convenient reach of a workman.

Another object of the invention is to provide a tool cabinet wherein the body portion thereof has a flat top of sufficient area to allow parts removed from an automobile to be placed upon the top after being removed. Therefore the tool cabinet will serve as a work bench as well as serving as a cabinet for holding tools, spare parts, and the like, used for making repairs to an automobile.

Another object of the invention is to provide the cabinet with a tool box carrying clips so arranged that screw drivers, wrenches, and other tools may be supported in convenient position when not in use.

Another object of the invention is to provide the cabinet with drawers movable to opened and closed positions and adapted to be secured when closed so that they may not be opened by unauthorized persons and tools or materials kept in the drawers removed.

Another object of the invention is to provide a tool cabinet having a tool box of such formation that it may be removed and closed and easily carried from one place to another if necessary.

The invention is illustrated in the accompanying drawings wherein:

Fig. 1 is a perspective view of the improved cabinet.

Fig. 2 is a sectional view taken vertically through the forward portion of the cabinet along line 2—2 of Figure 1.

Figure 3 is a fragmentary view upon an enlarged scale along the line 3—3 of Figure 5 and illustrating the manner in which jars for holding bolts, nails, and the like are removably supported.

Fig. 4 is a perspective view showing the manner in which a handle for a tool box is secured to a post at the back of the cabinet.

Fig. 5 is a vertical sectional view taken transversely through the cabinet along the line 5—5 of Figure 1.

Fig. 6 is a fragmentary sectional view taken along the line 6—6 of Figure 5.

Fig. 7 is a sectional view taken along the line 7—7 of Figure 6.

Fig. 8 is a fragmentary view of the means for securing drawers closed.

The cabinet which is indicated in general by

the numeral 1 may be of any dimensions desired and has a flat top 2 so that the cabinet may be used as a work bench or table. Drawers 3 and 4 are mounted for sliding movement into and out of the cabinet to closed and opened positions and under the drawer 4 is a space 5 open at its front so that jacks and other heavy tools may be placed in the lower portion of the cabinet upon the bottom 6 thereof when not in use. Bearing brackets 7 extend downwardly from the cabinet at the front and back thereof and carry shafts 8 upon which wheels 9 are mounted and thus allow the cabinet to be easily rolled along a floor from one place to another. The end walls 10 of the cabinet carry extensions 11 forming pockets or chambers in which drawers 12 are slidably mounted for movement to closed and open positions, and at its rear corners the cabinet carries vertically extending posts 13 which are formed of angle metal and serve to brace and support a panel 14 formed by the upwardly projecting portion of the rear wall of the cabinet. The front and rear end walls of the chambers 11 are extended upwardly to provide supports 16 for protruding ends of the top 2 and under these protruding ends of the top are mounted brackets 17 formed from metal rods. The protruding end portions of the top have openings 18 formed through them to receive and hold cylinders removed from an engine of a motor vehicle to be repaired. An elongated block or holder 19 is formed with vertically extending openings or bores 20 to receive the stems of engine valves which need to be cleaned or ground, and this block is disposed at one end of the cabinet and provided with ears 21 to receive pins 22 by means of which the ears are pivotally connected with ears of a bracket 23 secured against and projecting transversely from the post at the said end of the cabinet. Feet 24 extend downwardly from front and rear ends of the block transversely thereof so that when the pins 22 are removed and the block carried to a room in which the valves are to be ground, cleaned, or otherwise repaired the block may be set upon a work bench and supported by the feet.

In order to allow the drawers 3 and 4 to be secured in closed position there has been provided a metal rod 25 which extends longitudinally of the cabinet and is rotatably mounted through openings in end walls 10, one end portion of the rod being bent to form a transversely extending handle 26 by means of which the rod is turned to swing its crimped portions or arms 27 from the depending position shown in full lines in Figure 2 to a raised position in which they extend horizontally, as indicated by dotted lines in this figure. At its free end the handle is bent to form a U-shaped eye or hand hold 28 of such size that

when the handle is in the depending position shown it may pass through a slotted leaf 29' of the hasp 29. A padlock 30 may then be passed through the eye 28 and the handle will be securely held stationary. The arms 27 will thus be retained in the depending position and since they overlap the rear or inner end walls of the drawers 3 it will be impossible for an unauthorized person to draw the drawers outwardly to an opened position. A resilient clip 31 is provided to hold the handle raised. Midway its length the rod 25 is bent or crimped to form a crank 32 about which is loosely engaged an eye 33 formed at the upper end of a pin 34. This pin extends downwardly from the crank between the drawers 3 with its lower end portion slidably passing through an opening formed through a rail 35 mounted longitudinally of the cabinet against the rear wall 15 thereof. When the handle is swung downwardly to turn the rod 25 and swing the crank downwardly the lower end of the pin moves downwardly into overlapping engagement with the rear wall of the drawer 4 to secure the drawer closed, as shown in Figure 2, but when the crank is swung upwardly to the horizontal position shown in Figure 5 and the pin drawn upwardly with it the lower end of the pin will be above the drawer 4 and this drawer may be slid forwardly and outwardly to the opened position.

In order to carry a supply of screw drivers, wrenches, and other small tools there has been provided a tool box 36 mounted at the rear of the cabinet in upright position against the panel 14. This tool box consists of companion sections 37 connected with each other by hinges so that they may be swung from a closed position to an opened position in which they will be disposed in side by side relation to each other and will extend for substantially the full length of the top of the cabinet along the rear edge thereof. The opened tool box fits between the corner posts 13 and its sections carry pivoted anchoring members 38 which are U-shaped and formed from stiff metal rods and have their upper and lower arms bent at their ends to form pintles 39 engaged through bearing brackets 40 carried by the box sections. When the anchoring members are swung to the extended position shown in Figures 1 and 4 they engage about the posts and hooks 41 carried by the posts may then be moved into position to engage upper arms of the anchoring members and hold the opened box in place against the panel 14. Fastener members consisting of a hasp 42 and staple 43 are provided so that when the box sections are closed a padlock may be applied to secure the box closed. Handles 44 are pivoted to upper ends of the box sections so that when the tool box is removed from the cabinet and closed it may be conveniently carried from one place to another for use. Strips of resilient metal which are bent to form series of clips 45 are secured at their ends to rear walls of the box sections by bolts 46 which also pass through backing strips 47 to which the clips are held by loops 48, and from an inspection of Figure 6 it will be seen that when screw drivers, wrenches, and similar tools are thrust into place between the clips they will be gripped and firmly held until removed for use. One box section has secured to its rear wall a metal strip 49 having portions bent to form downwardly tapered sockets 50 through which pliers may be thrust to hold the pliers in the box section when not in use. Drawers 51 for holding small tools, replacement parts, and the like are slidably mounted under panels or shelves 52 and 75

in order to permit these drawers to be easily drawn outwardly to an opened position the shelves are formed with finger-receiving openings 53. Glass jars 54 are provided for holding screws and bolts of various sizes, and these jars have their threaded metal tops or covers 55 mounted against under faces of upper ends of the box sections. By unscrewing the jars from the covers and placing them upon the top of the cabinet screws or bolts in the jars may be removed for use and the jars then again screwed into engagement with the covers.

A cabinet and companion tool box of the improved construction will be very useful in garages, service stations, machine shops and the like since the cabinet may be rolled along the floor to a position close to an automobile or machine to be repaired and the tool box removed from the cabinet and closed and conveniently carried from one place to another. Since the tool box may be closed and locked and the drawers 3 and 4 of the cabinet secured in closed position they may be securely held against unauthorized opening and removal of tools and other articles from them.

Having thus described the invention, what is claimed is:

A device of the character described comprising a cabinet having a flat top and a panel projecting upwardly along the rear edge of the top, posts extending upwardly from the rear edge of the top at ends of said panel, a tool box formed of sections having side walls hinged to each other and thereby mounted for pivotal movement from a closed position to an opened position in which the sections are in side by side relation to each other and the hingedly connected side walls of the sections are in face to face engagement with each other, the opened tool box resting upright upon the top of the cabinet and being disposed between the posts and flat against the panel with its upper portion projecting upwardly above the panel, anchors carried by said sections and movable from a retracted position back of the opened sections to an extended position in which they project outwardly from the outer side walls of the said sections, said anchors having portions bent forwardly and being in position for engaging about portions of the posts above the panel, and hooks carried by said posts for engaging across the forwardly projecting portions of the anchors and releasably securing the anchors in engagement with the posts.
